UNITED STATES PATENT OFFICE.

ALBERT W. SAELESSER, OF GRANITE CITY, ILLINOIS, ASSIGNOR TO LIBERTY AUTO LOCK CO., OF ST. LOUIS, MISSOURI, A CORPORATION OF MISSOURI.

IGNITION-LOCK.

1,348,187.

Specification of Letters Patent.

Patented Aug. 3, 1920.

Application filed September 11, 1919. Serial No. 323,056.

To all whom it may concern:

Be it known that I, ALBERT W. SAELESSER, a citizen of the United States, residing at Granite City, in the county of Madison and

5 State of Illinois, have invented certain new and useful Improvements in Ignition-Locks, of which the following is a specification.

This invention relates to certain new and useful improvements in ignition locks the 10 peculiarities of which will be hereinafter described and claimed.

The main object of my invention is to provide an automatic lock for an ignition system such as that of an automobile, by 15 which the act of switching off the ignition will likewise automatically lock the switch in the switched off or cut out position without the air of the operator; a second object is to provide means whereby the key required for opening the automatic lock just mentioned must be removed from said lock before the current is cut in again, and thus avoid the danger from oversight in not removing the key of the automatic lock.

20 In the accompanying drawing on which like reference letters indicate corresponding parts, Figure 1 represents a face view of an ignition switch with my improvements applied thereto and shown with the switch in its cut out position; Fig. 2 an edge view of the device shown in Fig. 1; Fig. 3 a sectional elevation of the casing taken on the line 2—2 of Fig. 2 and showing a face view of the interior parts; and Fig. 4 a sectional 25 side elevation of the parts, the section being taken on the line 3—3 of Fig. 3.

This automatic lock is especially adapted for use with the ignition switch of an automobile and will be so described to exemplify 30 its use and advantages, though it is understood that it may be used for ignition switches elsewhere located. Thus when it is desired to stop the engine connected to the ignition switch, said switch is thrown 35 to cut out the current and by such action in connection with my automatic lock, the switch is locked in its cut out position so that the engine cannot be started until the automatic lock releases its engagement with 40 said switch. Furthermore, with my lock I eliminate all danger of leaving the key of the said lock in the keyhole after unlocking the switch, since in my construction, the

switch cannot be fully operated until said key is withdrawn after the initial action of 55 the key on my lock in order to start the switch to throw in the ignition current.

Referring to the drawing, the letter A designates a stationary tubular stub on which is rotatably mounted a bushing B 60 preferably squared at its end as shown in Fig. 3, and provided with a slot C for engagement with the usual switch handle D. On this bushing B is fastened an insulating hub having a ribbed arm F. The hub is 65 slotted and an arched switch blade E is secured therein. The arm F oscillates between posts G and G' limiting the engagement of the switch blade E with contacts H and H' suitably wired to the magneto and battery respectively. The blade E is 70 in constant engagement with the contact I suitably wired to the frame of the machine, or otherwise to complete the circuit through either the magneto or the battery according 75 to which way the switch is thrown, and the ignition or spark plugs of the engine. Said contact I is suitably insulated by the usual asbestos plate J from the body plate K carried by the said posts G—G' and a third 80 post L,—the tops of which posts are drilled and threaded to receive screws that pass through the face plate M of an inclosing casing N, whereby said casing is readily mounted on said posts and may be as readily 85 removed therefrom by taking out said screws.

Referring to Fig. 3, the said switch blade E and rocker arm F are shown in their neutral position which they assume when 90 the handle D is thrown to a vertical position in order to stop the engine running. It is this position of the switch that I automatically lock, and I do this by means of a spring-actuated plate O having two prongs 95 with beveled faces T and T', providing a notch Q between said prongs in which is inserted the upper end of said rocker arm F. The said plate is slidably mounted in suitable guides in said casing, and provided 100 with springs P—P acting downward so as to engage the upper end of said arm F automatically when the arm passes under said plate and raises the plate, by engagement with one of the beveled faces, to the upper 105 position indicated by dashed lines in Fig. 3.

When the arm F has reached the vertical position under the notch Q, the spring plate will automatically engage said arm and hold it from movement in either direction until 5 the plate O is unlocked.

A suitable lock R for this spring-actuated plate is provided and the bolt of said lock is adapted to raise the plate O to the position indicated by dashed lines, and such lifting 10 of the said plate must be effected before the switch arm and its blade E can be released. The bolt of said lock is a spring bolt, so that the downward tendency of the plate O under the action of the springs P—P will tend 15 to return the spring back bolt of the lock when the key S is released by the hand of the operator and remains in the key hole. Thus when the key S is inserted and the plate O is raised by the spring back bolt 20 of said lock R, the switch handle D can throw the switch arm and blade to the position indicated by dashed lines Fig. 3, and the springs P will return the plate O to the position shown in full lines Fig. 3 with the 25 beveled face of one of the prongs in position to be engaged by the arm F to raise the said prong and its plate when the arm is thrown to a neutral position once more.

Through carelessness the key S may be 30 left in the key hole, and to avoid this difficulty I provide a guard plate U Figs. 1 and 4, preferably mounted upon the squared end of the rotatable bushing B carrying the switch blade, so that the guard plate U will 35 turn when the switch is thrown, as indicated in Fig. 1 by dashed lines. In said guard plate is an opening V opposite the lock R when the plate is in the position shown by full lines Fig. 1. When said opening V registers with the key hole of the lock R, the 40 switch is already locked by the plate O as above described and the ignition is cut out, and cannot be thrown in again until the lock R is operated by the key S, which can 45 be passed through the hole V registering with the key hole. The plate O is thus raised and the switch is released, and the switch handle D can be turned enough to bring the top of the arm F under one of the 50 prongs so the prong will ride on the arm, before the edge of the hole V will stop the guard plate from further movement by engaging with the key S. Therefore the key S must be removed from the key hole before 55 the switch handle D can be operated to the full engagement of the blade E with one or the other of the contacts H or H'. This makes it impossible to start the engine again without first unlocking the switch 60 and then removing the key in order to throw the switch fully either to the magneto or battery contact.

The guard plate U besides being engaged by the square end of the bushing B, is retained by the turned over edges n of the 65

casing, so that the edges of said guard plate rotate freely within the groove thus formed but cannot be readily removed from the grooves. Additional safety is provided by an inwardly projecting rivet W Figs. 1 and 70 4, the head of which is inside the top plate of the casing and operates in a slot 5 Fig. 1, as the guard plate is rotated.

The guard plate also covers the fastening screws that engage the posts G, G and L, 75 and are countersunk in the top plate end of the casing. The whole casing therefore cannot be removed by taking out these screws, when the guard plate and switch are in their safe position shown in Fig. 1. In order 80 however to fasten this casing to the supporting posts, I provide openings 6 that respectively register with their adjacent screws, only when the switch and guard plate are thrown to one side or the other of 85 the position shown by full lines in Fig. 1. Therefore when the switch is locked the said openings 6 do not register with the adjacent screws, and the latter cannot be taken out nor the casing thus removed entirely, as 90 might otherwise occur. Only when the engine is running on magneto or on battery will the guard plate be thrown in such a position that the opening 6 will register 95 with the adjacent screws.

I do not limit myself to the exact construction shown.

Thus it is evident that the act of cutting out the ignition to the engine of an automobile, as commonly done when stopping 100 the machine, will likewise automatically lock the machine against theft; the engine can not be started again till the safety key S is used to allow the switch to close the ignition. Furthermore, the owner after unlocking the switch, must take out the safety key after the initial movement of the switch, in order to fully close or throw in the switch; he will not be able to leave the key in the lock by oversight, as frequently occurs otherwise. 110

I claim:

1. A device of the character described, comprising a rotary ignition switch having an insulated arm, contacts and operative 115 wires, a spring-actuated plate having double prongs beveled on opposite sides forming a recess between them that is automatically engaged by the movement of said arm in either direction and thus locks said switch, and means temporarily to disengage said plate to unlock said switch, substantially as described.

2. A device of the character described, comprising an ignition switch having contacts and operative wires, a key-controlled 125 automatic lock effecting locking control of said switch when the switch is open, a guard plate operated by said switch and having a key opening registering with said automatic 130

lock when the switch is open, but covering said automatic lock when the switch is closing, substantially as described.

3. A device of the character described comprising a rotary ignition switch having contacts and operative wires, a casing having fastening screws, a guard plate located above said screws and rotated together with said switch, and having openings that register with said screws only when the switch is closed, substantially as described.
4. A rotary ignition switch having con-

tacts and operative wires, a key-controlled automatic lock for said switch, an inclosing casing having fastening screws in the top 15 and a key opening, a guard plate rotatably mounted on top of said casing and operated in conjunction with said switch and having openings that register with said key and do not register with said screws when the 20 switch is open, substantially as described.

In testimony whereof I have affixed my signature.

ALBERT W. SAEGESSER.
